M. T. Finney

Attorney

UNITED STATES PATENT OFFICE.

CLEON M. HANNAFORD, OF RICHMOND, VIRGINIA.

ONE-PIECE HANDLE FOR ANGLE COCKS.

Application filed December 5, 1923. Serial No. 678,740.

To all whom it may concern:

Be it known that I, CLEON M. HANNAFORD, a citizen of the United States, residing at Richmond, in the county of Henrico and State of Virginia, have invented a certain new and useful Improvement in One-Piece Handles for Angle Cocks, of which the following is a full, clear, and exact description.

The object of this invention is to provide a handle for operating angle cocks which will protect the parts from the weather and foreign substances and simplify the replacement of the handle when broken or damaged without disturbing the connection of the handle socket with the key or plug. In connection with this last statement it is noted that in the common standardized angle cock the handle socket and handle have been so constructed and assembled that in order to separate them and replace the handle it is necessary to disconnect the socket from the key or plug by driving out the pin that connects them, and the handle has been made with openings to provide for this removal of the pin. My invention is designed to avoid the necessity for disconnecting the handle socket from the key or plug when the handle is to be removed.

The invention consists of a one-piece handle for angle cocks, characterized by a closed head which covers the handle socket, the protruding end of the key or plug and the pin which connects them, said handle having a pivotal movement on the handle socket, and also a sliding movement relative thereto in the absence of the pivot pin to effect the connection of the handle with the handle socket or its disconnection therefrom, regardless of the pin which connects the handle socket and key or plug, as I will proceed now to explain and finally claim.

In the accompanying drawings illustrating the invention, in the several figures of which like parts are similarly designated, Fig. 1 is a side elevation showing an angle cock of ordinary construction provided with the handle of this invention. Fig. 2 is a top plan view of a part of the handle detached and showing in dotted lines the handle socket, the square on the key or plug and the pin connecting the last two. Fig. 3 is an inverted view of part of the handle. Fig. 4 is a cross section on line 4-4 of Fig. 1. Figs. 5, 6 and 7 are diagrammatic views, in elevation and at right angles to Fig. 1, illustrating the manner of dis-

connecting the handle from the handle socket in accordance with this invention.

The angle cock 1 may be of any approved construction, the body of which is provided with the stop lugs 2. The key or plug 3 is provided as usual with the squared portion 4, and on this squared portion is mounted, in any usual way, the handle socket 5 having laterally projecting lugs 6 on opposite sides. The handle socket and the squared portion of the key or plug are connected by the pin 7. This handle socket is also provided with the finger 8 which, in addition to any other function usual to this feature, cooperates with a recess 9 in the handle so as to cause the handle socket and the key or plug to turn with the handle.

The handle has the gripping portion 10 and the head 11, this head being of inverted cup-shape and in one piece with the part 10 and closed in on top and circumferentially so as to make a closed cap or housing that covers and conceals the subjacent parts, so that they are shielded from the weather and other foreign matter and also are protected from external violence.

The head 11 is provided with ears 12 pierced transversely and adapted to straddle the correspondingly pierced lug 13 on the handle socket, and these holes in the ears on the handle head and the lug on the handle socket are adapted to receive the pivot pin 14 by which the handle is connected with the handle socket and is capable of an up and down pivotal motion on the handle socket. The handle head is provided with the depending lugs 15 which cooperate with the stop lugs 2 on the body of the cock to lock the handle in any given position on the body. Projections 16 extend horizontally and rearwardly from the bottom of the handle head to engage the projecting lugs 6 on the handle socket to prevent the undue movement of the handle when it is lifted to clear the lugs 15 from the lugs 2 at the time the handle is to be turned to open or close the cock.

As will be seen by reference particularly to Figs. 2 and 3, the handle head is not a true circle but has a substantially flat vertical wall at its rear where the ears 12 are located.

So far as the operation of opening and closing the cock is concerned, it is substantially as usual, but the handle is applied to the handle socket and removable therefrom

in a wholly different way from the usual. As already stated, it is not necessary to drive out the pin 7 in order to disconnect the handle from the handle socket, but it is necessary to drive out the pin 14 only. When this pin 14 is driven out, as indicated in Figs. 5, 6 and 7, the handle is free to be tilted upwardly from the rear as indicated in Fig. 6, and then by a forward sliding movement in the direction of the grip, the parts 16 slide from under the lugs 6 and the handle is thereafter free to be removed from the handle socket without disturbing the handle socket. The assembly of the handle and the handle socket is accomplished by a substantially reverse series of movements to those just described. The pin 7 in the course of time becomes corroded or rusted so tight in place that it is quite difficult to remove it, and frequently adjacent parts are broken in the attempts to remove the pin. As already stated, by my invention the pin 7 does not have to be removed in order to change the handle.

I am aware that handles for angle cocks have previously been made in one piece, but so far as I am aware, they have not included a closed head which serves as a cap to cover in, conceal and protect the handle socket and its adjuncts from the lodging of dirt, ice, snow, rain, etc., as in this present invention; nor has a one-piece handle cock made with a socket-enclosing head had integral with said head means by which the handle may be readily applied to and removed from the handle socket by a sliding movement. Furthermore and particularly when the handle has a closed head and the top of the head has been made substantially flat, there is afforded a weight receiving surface to protect the subjacent parts from injury by a person stepping thereon or a weight falling or being placed thereon.

I have thus described my invention as applied to a standard angle cock equipment without changing any of the parts excepting the handle, but obviously the one-piece part-enclosing handle may be adapted to angle cocks of other makes than standard, and moreover, a handle of the described construction may be applied to other devices than angle cocks.

Variations in the details of construction and the arrangement of parts are permissible within the principle of the invention and the claims following.

What I claim is:—

1. A one-piece handle for angle cocks having a head provided with projections extending horizontally and rearwardly from its bottom, a handle socket having laterally projecting lugs, a valve key or plug to which the handle socket is attached, and interengaging means on the handle and handle

socket to pivot the handle detachably to the handle socket, said handle being attachable to and removable from the handle socket by manipulation of said pivoting means without disturbing the relation of said socket and the key or plug and lengthwise movement of the handle so as to clear its projections from the lugs on the socket. 65 70

2. A one-piece handle for angle cocks, having a closed-in cup-shaped portion or housing and rearwardly extending projections adapted to engage with lugs on a handle socket and to be disengaged therefrom by a sliding movement in the direction of the length of the handle without disturbing the handle socket. 75 80

3. A one-piece handle for angle cocks, having an inverted cup-shaped head, and means to connect it with an ordinary handle socket having stop lugs, said head having at its bottom rearwardly extending projections adapted to be engaged with and disengaged from the stop lugs by sliding movement of the handle in the direction of its length without disturbing the handle socket. 85

4. The combination of a one-piece handle for angle cocks, having an inverted cup-shaped head provided with rearwardly extending ears and with projections at its bottom, and a handle socket provided with a lug adapted to be pivotally engaged with the ears on the handle and with laterally projecting stop lugs adapted to cooperate with the projections on the head, the handle being separable from the socket by removing the pivot pin and sliding the handle in the direction of its length from off the handle socket, without disconnecting the handle socket from the angle cock key or plug. 90 95 100

5. A one-piece self-locking handle for angle cocks, having a head provided with projections extending horizontally and rearwardly from its bottom and also having a hinge element and a connecting pin for hingedly connecting it to the aforementioned handle socket on the angle cock, a handle socket having complementary hinge elements for the reception of the connecting pin and also having laterally extending lugs for cooperation with the projections on the said head, whereby the handle is capable of being detached from the handle socket by removing said connecting pin and moving the handle upwardly and transversely away from the handle socket in the direction of the length of the handle and without disturbing said handle socket. 105 110 115 120

In testimony whereof I have hereunto set my hand this 5th day of December, A. D. 1923.

CLEON M. HANNAFORD.
